Primary Examiner — Michael C Stout*Assistant Examiner* — Melvin L Davis(74) *Attorney, Agent, or Firm* — Grogan, Tuccillo & Vanderleeden, LLP(57) **CLAIM**

The ornamental design for an eyes and mouth for plush toy, as shown and described.

DESCRIPTION

FIG. 1 is a perspective view of an eyes and mouth for plush toy showing a new design;

FIG. 2 is a front view thereof;

FIG. 3 is a back view thereof;

FIG. 4 is a side view thereof;

FIG. 5 is an opposite side view thereof;

FIG. 6 a top view thereof;

FIG. 7 is a bottom view thereof;

FIG. 8 is a perspective view of an eyes and mouth for plush toy showing a new design;

FIG. 9 is a front view thereof; and

FIG. 10 is a back view thereof;

FIG. 11 is a side view thereof;

FIG. 12 is an opposite side view thereof;

FIG. 13 a top view thereof, and,

FIG. 14 is a bottom view thereof.

The broken line showing of the eyes and mouth for plush toy is for the purpose of illustrating portions of the article that forms no part of the claimed design.

1 Claim, 10 Drawing Sheets(56)
